UNITED STATES PATENT OFFICE

SAMUEL ZULLO, OF JERSEY CITY, NEW JERSEY

CIGAR CUTTER.

Application filed April 18, 1928. Serial No. 271,086.

The object of my invention is to provide a combined cigar lighter and cigar cutter by mounting a suitable cutting implement, knife or tool on a cigar lighter and reconstructing certain parts of the latter so as to obtain a cooperation of the two parts whereby to provide an efficient cigar cutter and at the same time retain the characteristic features of a modern pocket cigar lighter.

I refer herein to the pocket cigar lighters of the type comprising a small casing container provided with an ignition mechanism which, when operated, ignites a wick which is fed by a suitable fuel contained within the casing.

Accordingly my invention is embodied in a combined cigar lighter and cigar cutter arranged and constructed as hereinafter set forth and as is illustrated in the accompanying drawing in which

Figure 1 is a top view of a combined cigar lighter and cigar cutter embodying my invention.

Figure 2 is a similar view showing the knife opened.

Figure 3 is a side view.

Figure 4 is a top view showing a modification.

Figure 5 is a partial side view of the device shown in Figure 4.

Figure 6 is a sectional partial view of the filler cap or closure member illustrated in Figures 4, 5 and 7.

Figure 7 is a top view of still another modification.

The cigar lighter is identified by the hollow casing 10 containing a suitable wick and fuel material, not shown, and which is ignited by a suitable ignition mechanism generally designated by the numeral 11. Nearly all modern cigar lighters of the type herein disclosed have the ignition mechanism mounted on one end of the casing, while the other end is provided with one or more inlet openings closed by suitable closing members in the form of nuts or caps adapted to be screwed into the casing flush therewith. Some of the lighters have the inlet opening placed in the middle or centrally of the casing in the one

narrow rectangular end thereof. Others have the inlet opening placed near a corner or at the end of one of the narrow sides. My invention is applicable to both types of lighters and embodies certain features cooperating with either type to provide an efficient cutter and lighter.

For purposes of understanding and identification I call the one end of the lighter the ignition end 12, while the other end is called the cutter end 13. In Figure 3 the numeral 14 denotes the usual cap or cup which contains reserve supply of ignition material such as a small piece of pyroforic metal, not shown. 15 denotes the screw cap for closing the inlet opening. Lighters embodying the foregoing features are in common use and very popular.

The numeral 16 denotes a cigar cutter or blade pivoted at 17 on the cap 14 and is adapted, normally, to be held in a closed uncutting position as in Figure 1, or to be swung into an open, active, position as in Figure 2. The cigar is indicated by a dotted circle 18 and is held against the casing 10. The tip is cut off by swinging the cutter inwardly towards the casing in an obvious manner. The cutter has an end finger portion 19 overhanging the casing and a side finger portion 20 in the form of a depending overhanging flange adapted to serve as a finger rest for closing the cutter in the cutting operation. The cutter is opened by pressing along and against the end finger portion 19.

The closing cap or screw 15 is provided with a button 21, and the blade has a pressed up socket portion 22 adapted to snap in over and engage the button 21 to keep the cutter in closed position, and also to prevent accidental displacement of the screw 15. It has been found that by frequent use the screw 15 is apt to become loose and may get lost, and fuel may drop out into the pocket of the wearer. The cooperating button 15 and socket 22 prevents this.

The flange 20 serves as a finger rest when cutting and a stop when the cutter is not used. The socket and button serve as a stop to prevent accidental opening of the knife and also to keep the screw 15 in place. The

casing is provided with a cooperating knife edge 23. It will be noted that the cutting portion 24 of the cutter lies wholly within the area of the cutter end 13 of the lighter.

6 This is to prevent accidents.

Figures 4, 5 and 6 illustrate a cigar lighter in which the closing screw is located in the middle. Usually this screw has a solid body which is screwed into the casing and a top 10 which lies flush therewith. In this case, see Figure 6, the closing screw is in the form of a hollow plug 26 adapted to be screwed into the casing and which carries the usual spark metal supply cap 27. The plug has an annular top flange 28 for closing the casing flush therewith and a second upper annular flange 29 joined to the flange 28 by spacing feet or spaced portions 30, whereby an opening 31 is formed opposite the cutter blade 32 as seen in 15 Figure 4.

20 The cutter blade is carried by a handle 33 pivoted at 34 and provided with a finger portion 35. When not in use the cutter is in the position shown in Figures 4 and 5 where it will be seen that the handle and blade lie between the two flanges on the screw plug 26.

25 As seen in Figure 6, the handle is of a thickness to fit snugly between the plug flanges so as to maintain the cutter in closed position by friction as will be understood. When a cigar is to be cut, the cutter is opened, the cigar inserted as shown at 36 in Figure 6. Then the cutter is closed and the top 30 cut off. Small particles of tobacco may pass out through the slit or opening 31. The top of the cigar remains in the plug 26 and may be shaken out. Similarly when the lighter is to be filled, the cutter is swung to one side after which the plug may be unscrewed.

35 Figure 7 shows a modification in which a sliding cutter 38 is mounted on the lighter casing to slide between the plug flanges 28 and 29 to cut the cigar. The cutter is guided and positioned by guides 39, 39, and has a finger portion 40 and a stop 41 to limit its 40 sliding movements in either direction in an obvious manner.

45 It will be noted as a feature common to the three forms of cutters disclosed that the cutting portions lie wholly within the area of the end of the casing; that portions of the casing cooperate with the cutter for cutting operations and that the cutters do not materially alter the construction nor materially increase the manufacturing costs.

50 I claim:

55 A device of the character described comprising a blade provided with a curved cutting portion intermediate the ends thereof, a 60 box for supporting said blade, means for pivoting the blade at its one end on the outside of the box flat against one end thereof, a cutting edge on the box cooperating with the cutting portion on the blade, a catch element 65 on the box adapted to engage a cooperating

70 catch element in the blade to maintain the latter in normal non-cutting position on the box and a stop on the blade adapted to engage the side of the box to cause the said two catch elements to engage each other and to serve as a finger rest on said blade during a cutting operation.

75 SAMUEL ZULLO.
